SCOURING PAD HOLDER

Samuel Ziskind, New York, N. Y.

Application February 2, 1953, Serial No. 23,383

Term of patent 14 years

(Cl. D9—2)

To all whom it may concern:

Be it known that I, Samuel Ziskind, a citizen of United States of America, residing at New York, in the county of New York and State of New York, have invented a new, original, and ornamental Design for a Scouring Pad Holder, of which the following is a specification, reference being had to the accompanying drawing, forming part thereof.

In the drawing

Fig. 1 is a top plan view of a scouring pad holder, showing my new design;

Fig. 2 is a front elevation view;

Fig. 3 is a side elevation view;

Fig. 4 is a bottom plan view; and

Fig. 5 is an exploded elevation view of my new design.

I claim:

The ornamental design for a scouring pad holder, substantially as shown.

SAMUEL ZISKIND.
